UNITED STATES PATENT OFFICE

2,241,748

STACK SWITCH

Burton E. Shaw, Bristol, Ind., assignor to Penn Electric Switch Co., Goshen, Ind., a corporation of Iowa

Application September 11, 1939, Serial No. 294,408

6 Claims. (Cl. 200—138)

An object of my present invention is to provide a stack switch including a switch structure and a relay, together with a transformer for various circuits of the stack switch, the parts being of simple construction and of such design that the switch can be made comparatively small and inexpensive from a manufacturing standpoint.

A further object is to provide a stack switch having improved features of construction whereby better operation characteristics of the stack switch are obtained at less power consumption than in standard stack switches as found on the present-day market.

Another object is to provide a stack switch which includes a switching mechanism formed of a buckled leaf spring having an extension that contacts with the periphery of a notched disc which is controlled in accordance with temperature changes in the stack, the arrangement being such that very little power is needed to operate the switch from one position to the other, so that the motion of the temperature responsive element may be substantially magnified and yet snap action is secured to insure quick make and break, and eliminate the possibility of the contacts being jarred open by operation of the relay in the stack switch.

Still another object is to provide a relay which can be made sufficiently powerful, yet relatively small, to minimize current consumption and to minimize jarring of the stack switch as a result of operation of the relay from one position to the other.

More particularly, it is my object to provide a relay which has a solid core and a shading coil serving in addition to its shading coil capacity as a spacer between the relay and a panel on which the relay is mounted.

Among other objects of the invention, I provide a panel for the stack switch mechanism and the relay which is supported in position by a transformer supporting bracket and a pair of screws which retain the bracket in supported position, the panel and the bracket cooperating with each other and with the casing for the stack switch in such manner that the parts may be placed in their proper relative positions and then all of them held there by the mere insertion of two screws.

A further object is to provide a relay which has a hard silicon steel core and therefore loses all residual magnetism when current is discontinued, thus making it possible, by using hard silicon for a magnetic frame of the relay and an arma-

ture thereof, to permit the armature to touch the frame in closed position so that there is a maximum of holding power to guard against undesired opening of the relay as a result of voltage drop.

With these and other objects in view, my invention consists in the construction, arrangement and combination of the various parts of my device whereby the objects contemplated are attained, as hereinafter more fully set forth, pointed out in my claims and illustrated in the accompanying drawings. Although the invention is susceptible of a variety of embodiments, it is unnecessary to fully describe and illustrate more than one in order to give a full understanding 15 of the invention both from its structural and functional standpoints. Accordingly, I have illustrated a preferred and desirable embodiment of the invention in the accompanying drawings, in which:

Figure 1 is a front elevation of a stack switch embodying my invention, with the cover removed to show interior construction details;

Figure 2 is an enlarged sectional view on the line 2—2 of Figure 1 showing a switch mechanism actuated by a stack temperature responsive element. The switch is in closed position;

Fig. 3 is a view similar to Fig. 2 showing the switch in open position;

Figure 4 is an enlarged sectional view on the line 4—4 of Figure 1 showing relay mechanism of my stack switch. The relay is in open circuit position.

Figure 5 is a similar sectional view showing the relay in closed position;

Figure 6 is a sectional view on the line 6—6 of Figure 5;

Figure 7 is a perspective view of a combined spacer and shading coil, and

Figures 8 and 9 are sectional views on the lines 8—8 and 8—9 of Figure 4.

In the accompanying drawings, I have used the reference numeral 10 to indicate generally a casing. A tubular support 12 extends from the casing 10. A coiled bimetallic element 13 has one end connected to the tube 12 at 14 and its other end secured to an actuating rod 15. The bimetal element 13 is adapted to be inserted in the stack of an oil or gas burning furnace so as to respond to the temperature therein.

Within the casing 10, a disc 16 having a notched periphery is mounted on the rod 15. A panel 17 is supported in the casing 10 and has a notch 18 through which a portion of the disc 16 extends to cooperate with an extension 19 of a contact spring 20.

The contact spring 20 is mounted in buckled position between upper and lower arms 21 and 22 of a bracket 23. The spring 20 is buckled sufficiently to normally retain a contact 24 carried thereby against a stop screw 25. Opposite the stop screw 25 is a cooperating stationary contact 26 carried by a bracket 27.

The extension 19 is U shaped, as shown in Figures 2 and 3, having a terminal end 28 adapted to contact with the periphery of the notched disc 16. The terminal end 28 may be adjusted toward or away from the disc for proper operation of the stack switch contacts 24-26 by means of an adjusting screw 29. The U shaped extension 19 has an inherent tendency to contract in width and may be expanded or permitted to contract by rotating the adjusting screw 29 in the proper direction. As shown by dotted lines in Figure 2, as the disc 16 continues to rotate counterclockwise it will spring the extension 19 and the spring 20 and permit the notches of the disc to slip past the extension 19 without breaking the circuit across the contacts 24-26. Immediately upon reverse rotation of the disc, the switch will be thrown to the other position, as shown by solid lines in Figure 3. Upon continued rotation in a clockwise direction, the notched disc will slip past the extension 19, keeping the contacts open as illustrated by dotted lines.

The panel 17 at its upper end has a pair of projections 30 extending through perforations 31 in the casing 10 (see Figures 1 and 2). This positions the upper end of the panel, while the lower end thereof is positioned by resting on a seat 32 of a bracket 33. The back end of the bracket has a pair of projections 34 entering openings 35 of the back of the casing 10, as shown in Figure 3. The bracket 33 also has a pair of threaded ears 36 receiving screws 37 extended through the walls of the casing 10.

The bracket 33 has a pair of downwardly extending portions 38 (see Figure 1) terminating in perforated ears to receive screws 39 for supporting a transformer T. The bracket 33 accordingly serves both the purpose of a support for the transformer and a means cooperating with the casing 10 and the panel 17 to position the panel; the screws 37, when they are inserted in position, effecting retention of all the parts 33, T and 17 in their proper relation to the casing 10.

On the panel 17, I provide a safety switch SS, described in my copending application, Serial No. 294,409 filed September 11, 1939 and which therefore will not be described further in this application.

On the back of the panel 17, I mount a relay consisting of a coil 40, a core 41, a magnetic frame member 42 and an armature 43. A non-magnetic frame member 44 of brass or the like is secured to the core 41 by riveting the core as indicated at 45. This also retains the magnetic frame member 42 on the core.

The armature 43 is provided with a pair of notches 46 receiving a pair of projections 47 of the frame member 44. Adjacent the projections 47 the frame member 44 is provided with shoulders 48 against which the armature is retained by a relatively stiff spring 49. The lower end of the spring 49 is connected with an extension or tongue 50 of the frame member 44. This tongue may be bent downwardly, as shown by dotted lines in Figure 4, to increase the tension of the spring 49 without the necessity of having

5 to provide an adjusting screw for this purpose.

The frame member 44 has a fingerlike extension 51 bent to a position above the armature 43 to act as a stop therefor, as shown in Figures 4 and 6.

On the front of the panel 17 are a pair of stationary power contacts 52 and a stationary low voltage contact 53. Cooperating therewith are 10 a pair of movable contacts 54 and a single movable contact 55. The contacts 54 and 55 are carried by contact leaf springs 56 and 57. The spring 57 is secured to the armature 43 under a block of insulation 58, while the spring 56 is riveted to the upper end of the block as at 59. The block 58 is secured to the armature 43 by 15 a pair of rivets 58a.

The leaves 56 and 57 extend through openings 60a and 61a of the panel 17 so as to expose the contacts 54 and 55 on the front thereof where 20 they are readily accessible for inspection and cleaning. The leaves 56 and 57 are substantially straight, thus eliminating the necessity of bending dies for forming them, and the spring 56 is T-shaped, as shown in Figure 6, so as to 25 provide a bridging contact for the contacts 52. The T head arrangement of the spring 56 provides substantially equal contact pressure on both contacts 52 when the relay is in closed circuit position. The contacts 54 being mounted substantially above the pivot of the armature 43 on 30 the shoulders 48, give a good wipe to these contacts relative to the contacts 52 to keep them clean.

The core 41 is made of hard silicon steel, 35 which requires no machining and loses all residual magnetism when the coil 40 is de-energized. The frame member 42 and the armature 43 are likewise made of hard silicon steel, to provide for a maximum of loss of residual magnetism. 40 This makes it possible to have the armature contact the frame 42 at the point 60, illustrated in Figure 8, when the relay is in closed position. Since contact of the parts gives maximum attraction, this arrangement requires a considerable reduction in line voltage before the relay 45 drops out. Hard silicon steel also has the characteristic of requiring less current for operation, and therefore the coil 40 may be made relatively small.

To minimize eddy currents, a shading coil SC 50 is provided consisting of a piece of copper formed as illustrated in Figure 7. An opening 61 therein receives a central pole piece 62 of the frame member 42 (see Figure 8), the frame member being slotted as at 63 to provide for the shading 55 coil SC.

The opening 61 of the shading coil is formed in a leg 64 thereof, while another leg 65 at substantially right angles to the leg 64 serves as a spacer between the frame member 42 and the panel 17. 60 Screws 66 extend through the panel and are threaded into the frame member 42, the leg 65 of the shading coil being notched at 67 to provide clearance for the screws.

My invention has been described in the foregoing specification and illustrated in the drawings more or less precisely as to details. It is to be understood, however, that changes may be made in the arrangement and proportions of parts and equivalents may be substituted without departing from the spirit and scope of the invention as set forth in the appended claims.

What I claim as my invention and desire to secure by Letters Patent of the United States is:

1. In a stack switch, a casing, a notched disc

in said casing, a switch coating therewith, temperature responsive means for rotating said disc, said switch comprising a buckled leaf, a contact carried thereby, a stationary contact for engagement therewith, a projection from said buckled leaf, said projection being U-shaped, an adjusting screw carried thereby to open or close the U, the free end of said projection engaging the periphery of said notched disc to be swung in one direction or the other by rotation of the disc in opposite directions and consequent movement of said buckled leaf with snap action from one circuit controlling position to the other.

2. In a stack switch, a notched disc, a switch coating therewith, temperature responsive means for rotating said disc, said switch comprising a buckled spring leaf, a contact carried thereby, a stationary contact for engagement therewith, a projection from the side of said buckled leaf, a disc engaging element on the free end of said projection and engaging the periphery of said notched disc to be swung in one direction or the other by rotation of the disc in opposite directions and consequent movement of said projection and thereby said buckled leaf with snap action from one circuit controlling position to the other.

3. In a stack switch, a notched disc, temperature responsive means for rotating said disc, a switch comprising a buckled leaf, a contact carried thereby, a stationary contact for engagement therewith and a projection from said buckled leaf, said projection being U shaped, an adjusting screw carried thereby to open or close the U, the free end of said projection engaging the periphery of said notched disc to be swung in one direction or the other by rotation of the disc in opposite directions.

4. In a stack switch, a notched disc, temperature responsive means for rotating said disc, a switch comprising a buckled leaf, coating contacts controlled by swinging thereof in opposite directions, a projection from one side of said buckled leaf, a U-shaped element having one arm connected to said projection and its other arm engaging the periphery of said notched disc to be swung by rotation of the disc in opposite directions and thereby effect movement of said buckled leaf with snap action from a position with said contacts open to one with them closed or vice versa.

5. In a stack switch, temperature responsive means, a disc rotatable thereby, a switch comprising a buckled leaf, a contact carried thereby, a stationary contact for engagement with said contact of said leaf, a return bent projection from said buckled leaf, an adjusting screw for adjusting the distance between the sides of said return bent projection, the free end of said projection engaging the periphery of said notched disc to be swung on one direction or the other by rotation of the disc in opposite directions, and subsequent movement of said buckled leaf with snap action from one circuit controlling position to the other.

6. In a switch structure, a notched disc, temperature responsive means for rotating said disc, a switch comprising a buckled spring leaf, coating contacts controlled by buckling thereof in opposite directions, and a U-shaped element having one arm secured to said buckled leaf and its other arm engaging the periphery of said notched disc to be swung by rotation of the disc in opposite directions and effect movement of said buckled leaf with snap action.

BURTON E. SHAW.
